UNITED STATES PATENT OFFICE.

ALBERT A. BAKER, OF ANSONIA, CONNECTICUT, ASSIGNOR, BY MESNE ASSIGNMENTS, TO FARREL-BIRMINGHAM COMPANY, INCORPORATED, OF ANSONIA, CONNECTICUT, A CORPORATION OF CONNECTICUT.

ROLL-GRINDING MACHINE.

Application filed August 28, 1924. Serial No. 734,754.

This invention relates to roll grinding machines, and more particularly to that class of grinding machines employed for grinding rolls such as are used, for instance, in connection with rolling mills, calendering machines, and other relatively heavy work, and particularly for rolls designed to be used upon heated material, such as hot steel plates, in which case the roll becomes heated and expands and for this reason it is necessary to crown or concave the roll, so that the plates will not emerge from the rolls thinner at the central portion thereof than at the edges. In preparing rolls of this character, the operation becomes a real grinding operation, as a considerable amount of material must be removed from the roll, as distinguished from a polishing or finishing operation sometimes performed when straight rolls are redressed.

Machines of this character usually employ a carriage which travels to and fro over the bed of the machine upon slides or ways; and where a considerable amount of material is removed from the roll, the grit and filings find their way to these slides or ways, and as a result the ways soon become so badly worn that it is necessary to re-finish them.

In prior machines of this character the ways upon the bed had usually been V-shape in form, the vertex of the V being disposed lowermost, so that the way in effect constitutes a trough, and any dirt, grit or filings falling upon these ways are carried to the bottom of this trough by the lubricant discharged thereupon, so that an accumulation of this extraneous material occurs within the trough of the way and serves to shorten the useful period thereof on account of the increased wearing effect.

One object of my invention, therefore, is to provide an improved roll grinding machine of this character, wherein the ways upon which the carriage moves will be cleansed of the grit and impurities likely to cause wear, and from which the grit and impurities will be shed so as not to deleteriously affect the surface of the way.

Another object of this invention is to pro-

vide a roll grinding machine with ways of such character that the wearing surfaces thereof will slope downwardly so that there will be a natural gravitational tendency for the grit and impurities to be removed from the way.

A still further object of the invention is to provide an improved lubricating system for ways of this character, such that the lubricant will be discharged upon the ways at the highest point thereof, so that the entire surface will be washed and cleansed of grit and impurities by the lubricant supplied thereto.

A still further object of the invention is to provide an improved lubricating system for the carriage ways of a roll grinder, so that the lubricant which has cleansed the ways of foreign material will discharge this material during its return to the tank and pump from which it is again supplied to the ways. The material carried in suspension by the lubricant will, according to my invention, be entirely removed from the ways and deposited in open channels which may readily be cleansed, and which are so located that this material will not prevent the free return of the lubricant to the pump.

To these and other ends the invention consists of the novel features and combination of parts to be hereinafter described and claimed.

In the accompanying drawings:—

Fig. 1 is a top plan view of a roll grinding machine embodying my improvements;

Fig. 2 is an end elevational view of the same;

Fig. 3 is an end elevational view of the machine bed and carriage showing the inverted V-shaped ways;

Fig. 4 is a transverse sectional view of one of the ways on line 4—4 of Fig. 5;

Fig. 5 is a bottom plan view of one of the ways.

The particular embodiment of my invention which I have selected to illustrate in the accompanying drawings comprises a bed 10 which may be of any proper or suitable configuration or shape to properly support the various machinery designed to be car-

ried thereon. The mechanism supported upon this bed may generally consist, as shown in Fig. 1, of a headstock A, a tailstock B, a reciprocating carriage C having mounted thereon carriage operating and reversing mechanism D and grinding wheel mechanism E.

The headstock is provided with driving lugs 11 and a centering pin 12, between which and a centering pin 13 on the tailstock the roll to be ground is held in the proper position. The headstock may be rotated by the motor 14 through the chain driving mechanism 15.

As shown in Fig. 1, the work supports just described are mounted at one side of the bed 10. Upon the other side are arranged two slides or ways 20 and 21, as shown more especially in Fig. 3, upon which the main carriage C is adapted to rest. Above these ways may be arranged suitable guards 22 and 23, so as to prevent, as far as possible, grit or other foreign material resulting from the grinding operation from falling upon the ways. The upper bearing surfaces of the ways, as shown in Figs. 3 and 4, are so arranged that the sides slope downwardly from an intermediate crest or ridge so that any dirt or grit falling thereon will have a tendency to work down the sloping sides of the ways and fall therefrom into the channels 25, 26, 27 and 28 which extend lengthwise of the bed throughout the length of the ways. As shown in Fig. 4, the upper surfaces of these ways are formed in the shape of an inverted V in cross-section, the sloping sides 29 and 30 being inclined toward the intermediate crest or vertex 31.

Upon the lower side of the carriage C are provided bearing surfaces 32 and 33, complementally shaped relatively to the ways 20 and 21, so that an inverted trough is provided in the carriage, the sides of which bear evenly upon the sloping sides 29 and 30 of the ways 20 and 21. The carriage C is also provided with openings 34 and 35 through which the guards 22 and 23 extend, the guards being suitably supported by their ends beyond the range of the movement of the carriage.

As shown more particularly in Fig. 4, the ways 20 and 21 are each provided with side flanges 40 and 41 by which they may be bolted to the bed 10. At the lower part of the way the latter is cored out to provide a lubricant channel 42, through which, as will be hereinafter described, lubricating material is forced through the way by a suitable pump. Longitudinally of this channel a strengthening web 43 extends lengthwise of the way, and at intervals laterally extending webs 44 and 45 join the web 43 to the sides of the oil channel 42.

Channels or bores 46 extend upwardly at intervals from the lubricating channel 42

to the ridge of the way, at which point the latter is slightly concave to provide a channel 47, so as to permit the oil to rise within the bore 46 and flow from the channel 47 downwardly over the inclined sides 29 and 30 so as to thoroughly cleanse the ways of grit or other impurities resulting from the grinding operation. It will be apparent that the channel extends throughout the length of the ways, as shown in Fig. 3, and the oil or lubricant being distributed through this channel through the ducts 46 flows evenly therefrom over the entire bearing surface of the ways. The oil falling from the sides of the ways flows slowly or sluggishly through the return channels 25, 26, 27 and 28, so that its burden of foreign material held in suspension will be deposited therein, the oil falling through the openings 49 and 50, shown at the ends of the ways in Fig. 1, to a reservoir or tank 51 within the bed.

As shown more particularly in Fig. 3, the oil is drawn from this reservoir through a strainer 52 and pipe 53 by the pump 54 to which the pipe leads, and is delivered by the delivery pipe 55 to the branch pipes 56 and 57 connected to the ducts 58 leading through the edges of the ways to the oil channel 42. The pump is operated by a belt 59 leading from a pulley 60 upon the shaft of a sprocket 61 driven by the sprocket chain 15 from the motor 14.

It will be observed that the oil channel 42 is closed at the end opposite the duct 58 so that a pressure may be built up therein and cause the lubricant to rise in the ducts or bores 46 and emerge upon the ridge of the way, so as to flow downwardly over the entire bearing surface thereof and cleanse this surface thoroughly of all grit, dirt or other impurities which are washed downwardly due to the sloping character of the bearing surface into the return channels. The grit settling in these channels may be quite readily removed from time to time so as not to interfere too much with the carrying capacity thereof or the lubricant.

It will be understood that as shown and more fully described in the application of Henry E. P. Taylor, Serial No. 707,633, filed April 19, 1924, the carriage C upon which the carriage driving and reversing mechanism D and the grinding wheel operating mechanism E are mounted is caused to reciprocate back and forth over the bed 10 so that the grinding wheel traverses the length of the roll supported between the headstock A and tailstock B. For this purpose upon the carriage is provided the driving motor 63 and reversing mechanism 64 which it is not necessary to describe in detail in this application. The grinding wheel operating mechanism E includes a suitable crowning device, also described in the co-pending appli- 130

cation referred to above, by which the rolls may be suitably crowned or concaved to the extent desired.

It will be obvious, also, that notwithstanding the relatively large amount of metal which must be ground off the rolls in a device of this character, the grit and dirt and impurities resulting therefrom will be constantly washed off the ways, due to the sloping form thereof and to the cleansing or washing action of the lubricant which is forced to the highest point upon the way and permitted to flow downwardly over the entire bearing surface thereof.

15 While I have shown and described a preferred embodiment of my invention, it will be understood that it is not to be limited to all the details shown, but is capable of modification and variation within the spirit of 20 the invention and within the scope of the appended claims.

What I claim is:—

1. In a roll grinding machine, a bed, a carriage adapted to reciprocate upon said bed 25 and having grinding mechanism mounted thereon, a way upon the bed upon which said carriage is adapted to slide, said way being formed with a central ridge and bearing surfaces sloping downwardly and outwardly 30 from said ridge, and means for continuously supplying a lubricant along the ridge, the lubricant being supplied in sufficient quantity to wash the sloping sides of the way and remove any foreign material adhering thereto.

2. In a roll grinding machine, a bed, a carriage adapted to reciprocate upon said bed and having grinding mechanism mounted thereon, a way upon the bed upon which 40 said carriage is adapted to slide, said way being of inverted V-shape form, and means for forcing a lubricant under pressure through the apex of the way, the lubricant being supplied in sufficient quantity to wash the sloping sides of the way and remove any foreign material adhering thereto.

3. In a roll grinding machine, a bed, a carriage adapted to reciprocate upon said bed and having grinding mechanism mounted 50 thereon, a way upon the bed upon which said carriage is adapted to slide, said way being formed with a central ridge and bearing surfaces sloping downwardly and outwardly from said ridge, said way being provided 55 with a ridge channel, and means for continuously supplying a lubricant to said channel, the lubricant being supplied in sufficient quantity to flow over the bearing surfaces of the way and cleanse them of foreign material falling thereon.

4. In a roll grinding machine, a bed, a carriage adapted to reciprocate upon said bed and having grinding mechanism mounted thereon, a way upon the bed upon which 65 said carriage is adapted to slide, said way

being formed with a central ridge and bearing surfaces sloping downwardly and outwardly therefrom, said way being formed with a ridge channel extending substantially throughout the length of said way, and 70 means arranged interiorly of said way for supplying a lubricant to said channel, the lubricant being supplied in sufficient quantity to flow over the bearing surfaces of the way and cleanse them of foreign material 75 falling thereon.

5. A roll grinding machine comprising a bed, a carriage slidably mounted on the bed, roll grinding and crowning mechanism mounted on the carriage, a way upon which 80 said carriage is adapted to slide, said way having an intermediate ridge and bearing surfaces sloping downwardly from this ridge, means for continuously supplying a lubricant to the sloping surfaces of the way, 85 and channels extending along said way to catch the drip of lubricant therefrom.

6. A roll grinding machine comprising a bed, a carriage slidably mounted on the bed, roll grinding and crowning mechanism 90 mounted on the carriage, a way upon which said carriage is adapted to slide, said way having an intermediate ridge and bearing surfaces sloping downwardly from this ridge, means for continuously supplying a 95 lubricant to the sloping surfaces of the way, channels extending along said way to catch the drip of lubricant therefrom, and a lubricant reservoir into which said channels empty.

7. A roll grinding machine comprising a bed, a carriage slidably mounted on the bed, roll grinding and crowning mechanism mounted on the carriage, a way upon which 105 said carriage is adapted to slide, said way having an intermediate ridge and bearing surfaces sloping downwardly from this ridge, means for continuously supplying a lubricant to the sloping surfaces of the way, and open channels formed in the bed 110 and extending along said way to catch the drip of lubricant therefrom.

8. A roll grinding machine comprising a bed, a carriage slidably mounted on the bed, roll grinding and crowning mechanism 115 mounted on the carriage, a way upon which said carriage is adapted to slide, said way having an intermediate ridge and bearing surfaces sloping downwardly from this ridge, means for continuously supplying a 120 lubricant to the sloping surfaces of the way, channels extending along said way to catch the drip of lubricant therefrom, a reservoir arranged within the bed below the ways, and openings in the bed through which the oil 125 received in said channels flows into said reservoir.

9. In a roll grinding machine, a bed, a carriage mounted to slide upon said bed, a way upon which said carriage is adapted to

- slide, said way being provided with downwardly and outwardly sloping bearing surfaces, a channel upon said way between said surfaces whereby a lubricant supplied to the channel flows over said bearing surfaces to cleanse them of foreign material, return channels provided in the bed along the edges of the way to catch the wash therefrom, a reservoir provided in the bed, said bed being provided with openings through which the oil received in said channels flows into the reservoir, and means to force a lubricant from said reservoir to said channel provided in the way.
15. 10. In a roll grinding machine, a bed, a carriage mounted to slide upon said bed, a way upon which said carriage is adapted to slide, said way being provided with downwardly and outwardly sloping bearing surfaces, a channel upon said way between said surfaces whereby a lubricant supplied to the channel flows over said bearing surfaces to cleanse them of foreign material, return channels provided in the bed along the edges of the way to catch the wash therefrom, a reservoir provided in the bed, said bed being provided with openings through which the oil received in said channels flows into the reservoir, said way being provided with interior ducts communicating with said channel therein, and means to force a lubricant from said reservoir through said ducts into the channel.
30. 11. A roll grinding machine having a bed, a carriage mounted to reciprocate on said bed, roll grinding and crowning mechanism on said carriage, ways upon which the carriage is adapted to slide, each of said ways being provided with an interiorly formed oil channel extending therethrough, said way having a longitudinally extending ridge and a second oil channel formed thereon, ducts establishing communication between said channels, an oil reservoir, and means for supplying oil to said interiorly formed channel and forcing it through said ducts to the ridge channel.
35. 12. A roll grinding machine having a bed, a carriage slidably mounted upon the bed, a way upon which said carriage is adapted to slide, said way having an interiorly formed oil channel therein and a longitudinally extending supporting web provided in said channel, means for supplying oil to the channel, and means for conducting said oil from the channel to the bearing surfaces of the way.
50. 13. A roll grinding machine having a bed, a carriage slidably mounted upon the bed, a way upon which said carriage is adapted to slide, said way having an interiorly formed oil channel therein and a longitudinally extending supporting web provided in said channel, means for supplying oil to the channel, and means for conducting said oil from the channel to the bearing surfaces of the way, and an open channel for catching the wash from said bearing surfaces in which the foreign material washed from the way is adapted to settle.
65. 14. A roll grinding machine having a bed, a carriage slidably mounted upon the bed, a way upon which said carriage is adapted to slide, said way having an interiorly formed oil channel therein and a longitudinally extending supporting web provided in said channel, means for supplying oil to the channel, and means for conducting said oil from the channel to the bearing surfaces of the way and from which the oil is returned directly to said supplying means.
80. 15. A roll grinding machine having a bed, a carriage slidably mounted upon the bed, a way upon which said carriage is adapted to slide, said way having an interiorly formed oil channel therein and longitudinally and laterally extending supporting webs provided in said channel, means for supplying oil to the channel, and means for conducting said oil from the channel to the bearing surfaces of the way.
85. 16. In a roll grinding machine or the like, a bed, a carriage adapted to reciprocate upon said bed, a way upon the bed upon which said carriage is adapted to slide, said way being formed with a ridge and a bearing surface sloping downwardly and outwardly from said ridge, and means for continuously supplying a lubricant along the ridge, the lubricant being supplied in sufficient quantity to wash the sloping side of the way and to remove any foreign material adhering thereto.
95. In witness whereof, I have hereunto set my hand this eighteenth day of August, 1924.

ALBERT A. BAKER.
